US00D738714S

(12) **United States Design Patent**
Kuhmichel et al.

(10) **Patent No.:** **US D738,714 S**
(45) **Date of Patent:** **** Sep. 15, 2015**

(54) **NUT AND SEAL**

(71) Applicant: **Weber Maschinenbau GmbH**
Breidenbach, Breidenbach (DE)

(72) Inventors: **Christoph Kuhmichel**, Bad Berleburg (DE); **Franziska Rupp**, Breidenbach (DE); **Volkan Yokaribas**, Breidenbach (DE); **Steffen Biernath**, Neubrandenburg (DE)

(73) Assignee: **Weber Maschinenbau GmbH**
Breidenbach, Breidenbach (DE)

(**) Term: **14 Years**

(21) Appl. No.: **29/484,801**

(22) Filed: **Mar. 13, 2014**

Related U.S. Application Data

(62) Division of application No. 29/441,501, filed on Jan. 7, 2013, now Pat. No. Des. 704,543.
